Primary Examiner — George J Ulsh

Assistant Examiner — Christine Tucci

(57) CLAIM

The ornamental design for a garment as shown and described.

DESCRIPTION

FIG. 1 is a front perspective view of a garment showing our new design;

FIG. 2 is a front view thereof;

FIG. 3 is a rear view thereof;

FIG. 4 is a left side view thereof;

FIG. 5 is a right side view thereof; and,

FIG. 6 is a rear perspective view thereof.

The broken line showing of the figure is for environmental purpose only and forms no part of the claim. The other broken lines outside of the claim depict portions of the garment that form no part of the claim.

1 Claim, 6 Drawing Sheets
